UNITED STATES PATENT OFFICE.

WILLIAM M. McCONAHEY, OF PITTSBURGH, PENNSYLVANIA, ASSIGNOR TO WESTINGHOUSE ELECTRIC AND MANUFACTURING COMPANY, A CORPORATION OF PENNSYLVANIA.

TRANSFORMER INSULATION.

1,224,184.

Specification of Letters Patent.

Patented May 1, 1917.

Application filed January 30, 1914. Serial No. 815,330.

To all whom it may concern:

Be it known that I, WILLIAM M. McCONAHEY, a citizen of the United States, and a resident of Pittsburgh, in the county of 5 Allegheny and State of Pennsylvania, have invented a new and useful Improvement in Transformer Insulation, of which the following is a specification.

My invention relates to transformers and 10 particularly to means for insulating the current-carrying windings thereof.

In a usual form of transformer, the high and low-tension windings are composed of concentric coils which are embraced by a plurality of iron cores that provide circuits for the magnetic flux. In order to provide a 15 transformer of high operating efficiency, it is important that the amount of space occupied by the insulation applied to the windings shall be minimized in order to improve the "space-factor" of the transformer. To insure the high-tension winding of the transformer against grounding through the iron core, it is convenient to dispose the high-tension coil between two sections of low-tension winding and to interpose adequate insulating means where the high-tension winding is in proximity to the iron cores. 20 This arrangement minimizes the quantity of 25 insulating material required, and, consequently, precludes low operating efficiency and poor regulation of the transformer which result from a poor space-factor.

For a better understanding of my invention, reference may be had to the following 30 description and the accompanying drawing in which Figure 1 is a plan view, partially in section, of a transformer embodying a form of my invention; Fig. 2 is a view of a 35 portion of the transformer in transverse section, taken along the line A—B, of Fig. 1; Fig. 3 is a perspective view of a high-tension transformer coil constructed in accordance with my invention, and Fig. 4 is 40 an enlarged sectional view of a portion of the coil shown in Fig. 3.

The transformer comprises a high-tension winding 1 interposed between coil sections 2 and 3 of the low-tension winding, the said 45 windings comprising concentrically disposed coils substantially as shown in Fig. 1. Core members 4, 5, 6 and 7 embrace the high and low-tension coils and provide paths of low reluctance for the magnetic flux generated by current traversing the transformer

windings. The core members 6 and 7 are similar, as are the core members 4 and 5. Inasmuch as it is desirable that the mean turn of the transformer windings shall be as short as is consistent with satisfactory 60 operation, the portions of the core members that are disposed within the opening 8 are worked at higher magnetic densities than the portions of the cores that are external thereto. As the voltage usually impressed 65 upon the high-tension winding 1 is sufficient to disrupt ordinary insulation interposed between said winding and the core members, I provide some of the coils comprising the high-tension winding 1 with insulating channel pieces 9 to preclude the grounding of 70 said winding through the core members.

In Fig. 2, the arrangement of the transformer coils and core members is more clearly set forth. To improve the insulating 75 properties, and for convenience in winding and assembling, the high-tension winding 1 is divided into a plurality of coils 10, 10^a, etc., which are superposed, one above the other, and suitably bound together by means 80 of tape. The low-tension coil sections 2 and 3 are wound in the form of substantially long tubular members and of such dimensions as to permit of the interposition of the coils 10, 10^a, etc. The low-tension coil sections 2 and 3 are adequately insulated from the high-tension winding 1 and the core members by suitable insulating fabric. It will be seen that the core members are adjacent to the high-tension winding 1 only 85 where the insulating channel pieces 9 are interposed at the outer surfaces of the top and bottom coils of the high-tension winding, as shown on coil 10 of Fig. 3. The insulating channel pieces 9 are preferably 90 made of micarta which possesses a high dielectric strength and withstands severe stresses and high temperatures without impairing its insulating properties.

Inasmuch as the core members 4—5—6 100 and 7 are spaced apart, it is unnecessary to provide channel pieces 9 which extend the entire periphery of the high-tension winding 1. It is sufficient that the said channel 105 pieces be applied only where the core members are in close proximity to the high-tension coils. In Fig. 3, the channel pieces 9 are shown as applied to only those portions of the coil 10 which are in close physical contact with the core members. Upturned 110

edges 11 formed upon the channel pieces 9 provide a leakage path of substantially high resistance to preclude the "creeping" of the high-tension current in the coil 10 to the core members.

I prefer that the high-tension coils, which are to be equipped with the channel pieces 9, shall be wound substantially as indicated in Fig. 4. The layers that are wound with conductors 12, and are received by the channel piece 9, comprise fewer turns than the other layers of the coil. This arrangement permits the channel pieces 9 to be applied without causing objectionable open spaces to intervene between the low-tension coils 2 and 3 which would result if the channel pieces 9 were allowed to project beyond the outer surface of the coil.

From the above description, it will be apparent that, by the utilization of my invention in transformer construction, the quantity of insulating material may be considerably reduced from that required in transformers as heretofore constructed. At the same time, no sacrifice is made in the ability of the insulation to withstand the high-potential stresses to which the transformer may be subjected. My invention also improves the "space factor" of the transformer which results in high operating efficiency and better regulation of the terminal voltage.

I claim as my invention:

1. A transformer comprising high tension coils, inner and outer low tension coils co-extensive therewith, core members embracing the coils, insulating channel pieces interposed between the adjacent surfaces of said core members and the high tension coils, the outer conductor layers of the high tension coils being inclosed by the channel pieces and the other conductor layers comprising a greater number of convolutions than said outer conductor layers.

2. A transformer comprising concentrically-disposed coils, the high tension coils being interposed between the low tension

coils that are co-extensive therewith, a plurality of magnetizable core members embracing the coils, and insulating channel pieces interposed between adjacent surfaces of the high tension coils and the magnetizable core members, said channel pieces receiving a plurality of convolutions of the coil, and other convolutions thereof being superposed by the upturned edges of said channel pieces in order to improve the space factor of the transformer.

3. A current-carrying coil comprising a plurality of superposed conductor layers having a multiplicity of convolutions, and an insulating channel piece applied to an exposed surface of the coil and receiving some of said conductor layers, the conductor layers not inclosed by said channel piece comprising the greater number of convolutions per layer and extending to the outer surfaces of the upturned edges of said channel piece.

4. A current-carrying coil comprising a plurality of superposed conductor layers having a multiplicity of convolutions, and an insulating channel piece receiving some of said conductor layers, the remaining conductor layers extending to the outer edges of said channel piece in order to form a smooth-surfaced coil side.

5. A current-carrying coil comprising superposed conductor layers having a plurality of convolutions of a uniform conductor, and an insulating channel piece receiving some of said conductor layers, the remaining conductor layers not inclosed by said channel piece comprising convolutions that extend to the outer surfaces of the upturned edges of said channel piece.

In testimony whereof, I have hereunto subscribed my name this 23rd day of Jan., 1914.

WILLIAM M. McCONAHEY.
